COSMETIC HOLDER

Albert Hagel, Newark, N. J., assignor to Consolidated Safety Pin Company, Bloomfield, N. J., a corporation

Application April 6, 1933, Serial No. 664,746
Renewed February 26, 1937

1 Claim. (Cl. 206—56)

This invention relates to an improvement in cosmetic holders, particularly designed for a holder for lipsticks.

The object of the invention is to provide a simple construction of holder, the parts of which are readily struck up from sheet metal, and by which the cover may be opened and the lipstick projected by a single movement of a push button.

10 The invention consists in the construction as hereinafter described and particularly recited in the claim.

In the accompanying drawings:

Fig. 1 is a perspective view of a cosmetic holder 15 constructed in accordance with my invention, in the open position;

Fig. 2 is a top view, in the closed position;

Fig. 3 is a front view;

Fig. 4 is a sectional view on the line 4—4 of

20 Fig. 3;

Fig. 5 is a sectional view on the line 5—5 of Fig. 3;

Fig. 6 is a perspective view of the elevator, detached;

25 Fig. 7 is a sectional view on the line 7—7 of Fig. 4, showing the parts in the closed position;

Fig. 8 is a similar view, showing the parts in the open position;

Fig. 9 is a perspective view of one of the cover-30 members, detached;

Fig. 10 is a perspective view of the other cover-member, detached;

Fig. 11 is a perspective view of the top, detached; and

35 Fig. 12 is a perspective view of the bottom, detached.

In carrying out my invention, the casing is formed from two parts, the bottom part comprising a bottom 15 and sides 16, formed with flanges 17. The top part consists of a top 18, front 19 and back 20. Preferably the walls of both members are tapered and the top 18 is formed with a clearance opening 21, the front wall with a slot 22, and the rear wall with guide-40 ribs 23, and the ends of the top are extended and turned down, forming lips 24 which, when assembled, overlap the upper ends of the sides 16.

The sides of the front and back are also formed 50 with notches 25 to engage with indentations 26 in the flanges of the side walls between which the front and back extend, the lower ends of the front and back being held in separated position by ribs 27 formed in the bottom 15.

Pivots connected with the front and back, near the lower ends thereof, are cover-members 28, each comprising a yoke 29, a front wall 30, a spring-finger 31 and a top plate 32. Preferably the top 18 will be transversely bowed and the top plates 32 will be correspondingly shaped. The adjacent edges of the cover-members 28 have straight edges 33 and near their lower ends are formed with reversely-formed cam-notches 34.

5 Before assembling the casing, a container or elevator 35 is placed in the container in which it is guided for vertical movement by the ribs 23, and fixed to the container is a finger-piece 36 having a shank 37 which extends through the slot 22, between the edges 33 of the cover-members, and into engagement with the elevator, the cam-surfaces being located adjacent to the lower ends of the slot 22.

10 A lipstick 38 is placed in the elevator 35. In the closed position of the device, the spring-fingers 31 hold the top plates 32 together and close the opening 21. When the finger-piece 36 is raised, the first movement separates the adjacent edges 33 of the cover and moves the plates out of alignment with the opening 21. A continued upward movement of the finger-piece projects the lipstick through the opening 21 for use, and the cover-plates are maintained in the open position by the shank 37 between their adjacent edges, the elevator being guided between the ribs 23. When the finger-piece 36 is moved downward and approaches the lower end of the slot 22, the shank acts on the cam 34 and moves the two cover-members together and brings the plates 32 beneath the opening 21, the cover-members being normally held in their closed position by the action of the springs 31.

15 This construction permits of the production of a lipstick holder in an attractive form and of convenient shape, and one readily operated by 40 one hand of the user.

I claim:

A cosmetic holder comprising a casing formed in two parts, one comprising a bottom and side walls, and the other a top, front and back, these 45 parts being adapted to be connected together, an opening formed in the top, cover-members pivotally connected with the front and back and each having a top-plate adapted to close the opening in the top, an elevator within the casing, and means for raising the elevator and separating the cover-plates.

ALBERT HAGEL.
